UNITED STATES PATENT OFFICE.

OTIS R. ANGELL, OF HAVERHILL, MASSACHUSETTS, ASSIGNOR TO HAMEL SHOE MACHINERY COMPANY, A CORPORATION OF MASSACHUSETTS.

EDGE SETTER AND BURNISHER.

1,398,993.

Specification of Letters Patent.

Patented Dec. 6, 1921.

Application filed November 12, 1917. Serial No. 201,521.

To all whom it may concern:

Be it known that I, OTIS R. ANGELL, a citizen of the United States, residing at Haverhill, in the county of Essex and State 5 of Massachusetts, have invented certain new and useful Improvements in Edge Setters and Burnishers, of which the following is a specification, reference being had therein to the accompanying drawings.

10 This invention relates to machines for setting and burnishing the edges of shoe soles and more particularly to means for supporting and for reciprocating the operating tool.

15 In machines of the above type as at present constructed and in which cranks or eccentrics have been employed for reciprocating the tools, much annoyance has been caused by reason of the excessive vibration 20 produced, resulting in disagreeable noise and rapid wear of parts. It is an object of the present invention to so construct a machine of the above type as to eliminate all unnecessary machine parts and at the 25 same time to reduce undesirable vibration to a minimum.

It is a further object of the invention to provide in an edge setting machine a tool holder constructed to simultaneously hold a 30 plurality of tools and adapted to be so controlled as to present either of said tools in working position at the will of the operator.

Other and additional objects and advantages of the present invention together with 35 desirable details of construction and improved combination of parts will be hereinafter described and particularly pointed out in the claims.

Figure 1 is a side elevation of the operative parts of the tool supporting and operating mechanism. Fig. 2 is an end elevation of the same, and Fig. 3 is a plan view looking from above. Figs. 4, 5 and 6 are corresponding views of a second and 45 preferred form of the invention. Fig. 7 is a diagrammatic elevational view showing the operative mechanism as mounted in position on the machine frame, and Fig. 8 is a detail thereof.

50 1 is a hollow shaft mounted in suitable bearings and continuously driven from any convenient source of power, as by means of a pulley 1^x. Within said hollow shaft and carried thereby is a relatively fixed rod or 55 supporting-member 2. This rod may be held

in fixed position with respect to the frame of the machine by any suitable means, but is herein shown as provided upon its rearward extremity with a gear 3, which gear is arranged to mesh with a secondary gear or 60 rack 3^b (Fig. 7) adapted to be turned manually and to be fixed in either of two adjusted positions for a purpose which will be hereinafter described. The forward end of said rod 2 is provided integrally or otherwise 65 with an enlargement 4, such enlargement being slotted or bifurcated at its outer extremity to provide opposed arms 5 and 6.

Passing through suitably formed openings in said arms is a stub shaft or pindle 70 pin 7, said pin being provided with an enlarged head at one extremity and being screw-threaded at its opposite extremity for reception of a lock nut 8. Pivotedly supported upon said shaft or pin 7 is a rockable tool-holding head 9 adapted to vibrate in a vertical plane passing through the center of shaft 2. This tool-holding head 9 is provided with a pair of oppositely extending posts 10 and 11, said posts being 75 provided with suitably formed extremities 12 and 13 for the reception of tool holders of the type usually employed in machines of this character. Projecting from the posts 10 and 11, and in the plane of vibration of 80 said head are a pair of bracket arms 14 and 15, said arms being spaced from the main portion of the head 9 to form openings 16 and 17 therebetween. Fixed in aligned openings in said brackets and in the head and extending across said openings are a pair of 85 fixed pins 18 and 19, said pins forming the axes of rollers 20 and 21, the rollers herein disclosed having the form of oblate spheroids, this specific form of roller, however, 90 not being essential as rollers of any other suitable and desired form may be substituted therefor.

Fixed upon the end of the shaft 1 to rotate therewith is a disk-member 22, said 100 disk-member being provided upon its face with a groove or run-way 23. This groove or run-way, as may be seen from inspection of Fig. 3, is deeper at the part 25 than at the part 24 which is diametrically opposite the 105 same, the groove as thus described forming in effect a face-cam of varying depth.

The support 4 is so located with respect to the shaft 1 and disk 22 that the rollers 20 and 21 engage with the bottom of the 110

cam groove 23. From the above construction it will be appreciated that upon rotation of the shaft with its cam disk, the member 2 being held in relatively fixed position, 5 by reason of the travel of the rollers 20 and 21 over the high and low parts of the cam groove 23, the head 4 carrying said rollers and the tool-holding posts carried thereby will be rapidly vibrated in a plane parallel 10 to the axis of the shaft 1.

By reason of the fact that the operative parts in this machine are all located closely adjacent the bearings and that no long or heavy lever-members are necessary for securing the desired movement of the tool-carrying parts, very little vibration in the machine frame with its consequent noise and wear is produced, the machine as above constructed being almost noiseless in its operation, 20 while at the same time performing its work well and efficiently.

The machine herein disclosed as above described is provided with oppositely extending tool-carrying posts, and by reason of the arrangement described, embodying the gear 3 with means for turning the same and locking it in position, the relative arrangement of the posts 10 and 11 may be reversed, thereby permitting the use, as is common in machines of this general character, of separate tools for operating upon the shank and forepart of the shoe sole, the gear 3 and the described connections permitting reversal of the head as often as may 35 be desired.

As an example of means for turning and locking the supporting-member 2 reference may be had to Fig. 7, wherein is shown a gear segment 3^b fixed to a shaft 50 extending through the frame and having a hand lever 51 upon its forward end, such lever being provided with a locking pin 52 adapted to engage either of a pair of suitably formed sockets 54 in the frame, whereby the lever 51 together with gear segment 3^b may be locked at will in either of the two desired positions. While the locking means disclosed is well adapted for use in the present machine, it is to be understood that the invention is not limited thereto as any other and equivalent mechanism may be substituted therefor. In the modification shown in Figs. 4, 5 and 6 many of the parts correspond to the structure of the above described mechanism, and as to these parts it is believed to be only necessary to state the structure in the briefest manner. 1^a indicates the power driven shaft; 2^a the fixed supporting-member; 3^a the gear mounted 50 upon the same; 4^a the forked or bifurcated head carried upon said support; 5^a and 6^a the oppositely disposed arms of said forked-member; 7^a the pintle pin or shaft and 8^a the locking nut for the same.

65 Mounted to rock upon said pintle pin is

the vibrating tool-holding head 9^a, said head having extending therefrom in opposite directions the tool-carrying posts 10^a and 11^a. Upon the posts 10^a and 11^a is pivoted to oscillate in a horizontal plane a disk or yoke-member 30, said yoke-member being provided with arms 31 and 32 having journal openings 31^a, 32^a therein adapted for pivotal mounting upon the posts 10^a and 11^a. The yoke-member 30 has formed upon its 75 rearward face a groove 33 forming one element of a ball-race. Fixed upon the shaft 1^a is a disk 22^a having formed therein a groove 34, said groove forming the complementary ball-race element, the disk 22^a being also 80 provided with a flange 35 inclosing the circular portion of the yoke-member 30 carrying said ball-race 33. Inspection of Fig. 6 will show that the ball-race 34 is deeper at the part 25^a than at the part 24^a, thus forming 85 in effect a cam groove in the face of said disk. Between the ball-race elements 34 and 33 is mounted a continuous series of ball bearings 36, said bearings serving to transmit motion from the rotating disk 22^a to the 90 yoke-member 30.

Upon rotation of the shaft 1^a the race element 34 is rotated, causing the bearings held in the same to travel with relation to the respective race elements 34 and 33, and by reason of the inclined arrangement of the race element 34, such rotation will cause a rocking movement of the yoke 30 about its pivotal support. As the shallow portion of the groove passes the vertical plane, it will cause a rocking movement of yoke element 30 together with head 9^a about the pintle pin 7^a, thus producing that movement of the tool holders necessary for the proper function of the machine. As the shallow portion of the 100 groove, however, passes the horizontal plane, a rocking movement of yoke 30 about the posts 10^a and 11^a will be produced, this movement being an idle movement as far as the tools are concerned, its only function being to prevent jamming of the ball bearings in passing along the race which action would occur in this form of the invention due to the employment of the continuous series of bearings unless some provision of 110 115 this character were made.

It will be evident, therefore, that yoke 30 is given a wabbling motion which may be considered as vibration in a plane which is constantly rotating about the cam axis or as 120 vibrating in an infinite number of planes passing through the cam axis progressively advancing from one plane to another through a complete circle. The tool-holding head is normally held so as to be vibrated 125 in one of these planes, vibration of the actuating member in other planes being idle motions so far as the tool holder is concerned, while it is so held. When the tool holder is rotated to change tools, its plane of vibra- 130

tion rotates similarly to that of the actuating yoke 30.

While the form shown in Figs. 4, 5 and 6 is a preferred form of the invention, it is to be understood that the invention is not to be limited to the specific details of construction herein shown, but that it is to be construed as covering all modifications and variations of the same within the province of mechanical skill, and as included in the scope of annexed claims.

Having thus described the invention and its mode of operation what I desire to secure by Letters Patent of United States is,—

15 1. In an edge setting machine, in combination, an actuating shaft, a tool holding head, pivotal means supporting said head constructed and arranged to constrain said head to move normally in a plane passing through 20 the axis of the shaft, and means actuated by said shaft for imparting to said tool holder a simple oscillatory movement about said pivotal support.

2. In an edge setting machine, a tool 25 holder, means for oscillating the same about a normally fixed horizontal axis and means for adjustably positioning said tool holder in a vertical plane containing said axis.

3. In an edge setting machine, in combination, a tool holder provided with a 30 plurality of tool holding elements, means for pivotally supporting said holder to oscillate about an axis lying in a plane passing through two at least of said elements, and 35 means for oscillating said head about said axis in a second plane passing through at least two of said elements.

4. An edge setting machine having, in combination, a tool holder provided with a 40 pair of tool holding posts, pivotal means supporting said holder for oscillation in a plane passing through both of said posts, means for oscillating said holder, and means permitting said holder to be revolved in 45 a plane also passing through both of said posts.

5. An edge setting machine having, in combination, a tool holder having a pair of tool holding elements lying in the same 50 plane, pivotal means supporting said tool holder for oscillation in said plane, and means for moving said tool holder out of said plane.

6. An edge setting machine having, in combination, a tool holder, a plurality of tool holding elements thereon, a pivotal support for said holder, means for oscillating said tool holder in a plane passing through at 55 least two of said elements and substantially 60 perpendicular to the axis of said support and means for moving said holder in a plane containing said axis.

7. An edge setting machine having, in combination, a tool holder having a pair 65 of tool holding elements, means for oscil-

lating said elements in a common plane, and means for turning said tool holder about an axis lying perpendicular to said plane.

8. In an edge setting mechanism, a tool holder, means for vibrating said tool holder 70 about an axis, and means for progressively changing the direction of said axis.

9. In combination in a machine of the class described, a support, a rotatable cam-member, and a tool-holding head supported 75 to oscillate in a plane about a fixed axis at right angles to the axis of said cam-member and passing therethrough, rotation of said cam-member serving to rock the tool-holding head.

10. In an edge setting machine, in combination, a support, a rotatable cam-member, a shaft having its axis at right angles to and passing through the axis of rotation of said cam-member, a tool-holding head 85 mounted upon said shaft, and means for transmitting motion from said cam-member to said head.

11. In an edge setting machine, in combination, a rotary shaft, a single face-cam 90 fixed thereon adjacent the extremity thereof, a tool-holding head mounted to rock about an axis transverse of said shaft, and in a plane therewith and anti-friction means for transmitting motion from said cam to the 95 tool-holding head.

12. In an edge setting machine, in combination, a hollow shaft, and means for rotating the same, a cam mounted upon said shaft, a normally fixed shaft within said 100 hollow shaft, a tool-holding head pivoted upon the extremity of said fixed shaft and means for transmitting motion from said cam to the head.

13. In an edge setting machine, in combination, a normally fixed shaft having its extremity bifurcated to form opposed arms, a tool-holding head pivoted to rock between said arms, a hollow shaft or sleeve mounted upon said fixed shaft, a cam upon said hollow shaft or sleeve and means for transmitting movement therefrom to said tool holder.

14. In an edge setting machine a tool holder adapted to sustain a plurality of 115 tools, means for vibrating the same about a normally fixed axis and means for adjustably positioning said tool holder in a plane containing said axis of vibration and at right angles to the plane of vibration, whereby 120 to permit selective use of said tools.

15. In an edge setting machine a tool holder having a plurality of tool-holding means lying in the same plane, elements for vibrating said tool-holder in a plane 125 perpendicular to the plane of said tool-holding means and means for adjusting said tool holder in the plane of the tool-holding means to permit selective use of the several tools.

16. In an edge setting machine, a bearing- 130

member, a normally fixed shaft mounted therein having its end projecting beyond said bearing-member, means for turning said shaft, for adjusting the angular position 5 thereof, a tool-holding head mounted for vibration upon the projecting end of said shaft, and means for vibrating said head.

17. In an edge setting machine a rotary face-cam, means for rotating said cam, a 10 tool holder having a tool holding element, means for supporting said element to oscillate in a plane containing the axis of rotation of said cam, and anti-friction devices carried by said head and arranged for contact with said face cam, whereby rotation 15 of the latter serves to rock said head.

18. In a machine of the class described, a rotary disk provided with a groove in its face, said groove having high and low portions 20 constructed to act as a cam, a tool-holder provided with a tool holding element, said holder together with said element being arranged to rock toward and from said groove, and anti-friction devices engaging within said 25 cam-groove and acting to transmit motion therefrom to said tool holder.

19. In an edge setting machine, a support, a cam carried thereby, a tool holder, means supported by said tool holder and coöperating 30 with said cam to move said tool holder, a plurality of tool-holding elements immovably carried by said tool holder, and means adapted to bring selectively any of said tool-holding elements into position to present 35 its tool for use.

20. In an edge setting machine, a support, a cam carried thereby, a rotatable tool holder, means carried by said tool holder and coöperating with said cam to vibrate 40 said tool holder, a tool-holding element immovably carried by said tool holder and means for rotating said tool holder.

21. In an edge setting machine, a rotary cam, a tool holder extending across the face 45 of said cam and arranged to be vibrated thereby, and a pivot pin for supporting said tool holder, the axis of said pin being substantially perpendicular to that of the cam.

22. In an edge setting machine, a single 50 faced, rotary cam, and a tool holder pivoted adjacent the face of said cam and adapted to be vibrated thereby in a plane containing the axis of the cam.

23. An edge setting machine having, in 55 combination, a rotary shaft, a face cam fixed thereto and adjacent one extremity thereof, a pivot pin, means for supporting said pin at a point adjacent said extremity, a tool holding head mounted to rock upon said pin, and means for transmitting movement 60 from said cam to said head.

24. An edge setting machine having, in 65 combination, a rotary face cam, a pivot pin, means for supporting said pivot pin adjacent said cam and transversely of the

axis thereof, and a tool holding head pivotally supported upon said pin.

25. In an edge-setting machine, a jogging tool-holder, a cam-follower operatively connected therewith, and a rotary cam having 70 a single cam-face acting positively at all times upon said follower in a direction lengthwise of the axis of rotation to impart jogging movements to said tool-holder.

26. An edge setting machine having, in 75 combination, a rotary face cam, a tool holder movable toward and from said cam, a tool holding device fixedly carried by said holder and a plurality of elements having simultaneous contact with said cam and collectively operative to actuate said head.

27. In an edge setting machine, an actuating member arranged to vibrate in a plurality of planes, and a tool-holding head actuated thereby to vibrate in any single plane 85 of a plurality of planes.

28. In an edge setting machine, an actuating member arranged to vibrate in a plurality of planes, a tool-holding head arranged to be actuated thereby to vibrate in one of 90 a plurality of said planes, and means for selectively determining said plane.

29. In an edge setting machine, an actuating member arranged to vibrate in a plurality of planes, a tool-holding head arranged 95 to be actuated thereby to vibrate in selected ones of said planes, and means for progressively changing from one of said planes to another.

30. In an edge setting machine, an actuating member adapted to vibrate in a plurality of planes, a tool-holding head arranged to be actuated by the vibrations in a single plane of said actuating member, and means for progressively changing said plane. 100

31. In an edge setting machine, an actuating member adapted to vibrate in a plurality of planes, a tool-holding head arranged to be actuated by the vibrations in a single plane of said actuating member, and means 110 for determining said plane.

32. In an edge setting machine, an actuating member arranged to vibrate progressively in each of an infinite series of successive planes, a tool holding head arranged to be actuated by said member to vibrate in any one of an infinite series of planes, and means operative to constrain said head to vibrate in a single one of said planes. 115

33. In an edge setting machine, in combination, a support, a tool holding head mounted to rock thereon, an actuating member connected to move with said head, and also movable in a plane at right angles to the plane of movement of the head, a rotary disk having a cam groove cut in one face thereof and means for transmitting movement to said actuating member from said groove. 120

34. In an edge setting machine, in combi- 130

- nation, a support, a tool holding head pivoted thereto to rock in a substantially vertical plane, an actuated member pivoted to said head to swing in a horizontal plane, a 5 rotary face cam providing a cam path, and a cam follower engaging said path and said actuating member respectively and arranged to move said actuating member and thereby rock the head.
- 10 35. In a machine of the class described, a support, a tool-holding head pivoted to rock thereon, a yoke-member pivoted upon said head to swing in a plane perpendicular to the plane of movement of said head, a rotary cam, means for driving the same, and anti-friction means interposed between said cam and said yoke member.
- 15 36. In a machine of the class described, a support, a tool-holding head pivoted to rock thereon, a member pivoted to swing upon said head in a plane perpendicular to the plane of movement thereof, said member being provided with one element of a ball- 20 race, a rotating cam forming the other ele-

ment of said race and a series of anti-fric- 25 tion balls located between said elements.

37. In an edge setting machine, in combination, a support, a tool-holding head pivoted to rock thereon, said head comprising a pair of oppositely directed posts, a yoke- 30 member having spaced arms, said arms being pivoted upon the respective posts, and rotating means constructed and arranged to swing said yoke-member and said tool-holding head in planes at right angles to each 35 other.

38. In a machine of the class described, a support, a tool holder having a pair of oppositely directed posts and mounted to rock upon said support, a yoke-member pivoted 40 to swing upon said posts, said yoke-member being provided with one element of a ball- race, a rotating cam forming the other element of said race and a series of anti-friction balls located between said elements. 45

In testimony whereof, I have signed my name to this specification.

O'TIS R. ANGELL.
